(57) **CLAIM**

The ornamental design for soft top camper shell for pickup trucks with roof rack, as shown and described.

DESCRIPTION

FIG. 1 is a perspective view of the skeletal body of the soft top camper shell of the present invention;

FIG. 2 is a rear view of the skeletal body of the soft top camper shell of the present invention;

FIG. 3 is a front view of the skeletal body of the soft top camper shell of the present invention;

FIG. 4 is a side view of the skeletal body of the soft top camper shell of the present invention;

FIG. 5 is a front plan view of the skeletal body of the soft top camper shell of the present invention;

FIG. 6 is a perspective view of the soft top camper shell of the present invention with the cover on the skeletal body;

FIG. 7 is a rear view of the soft top camper shell of the present invention with the cover on the skeletal body;

FIG. 8 is a front view of the soft top camper shell of the present invention with the cover on the skeletal body;

FIG. 9 is a side view of the soft top camper shell of the present invention with the cover on the skeletal body;

FIG. 10 is a top plan view of the soft top camper shell of the present invention with the cover on the skeletal body;

FIG. 11 is a perspective view of the soft top camper shell of the present invention with the roof rack attached;

FIG. 12 is a rear view of the soft top camper shell of the present invention with the roof rack attached;

FIG. 13 is a front view of the soft top camper shell of the present invention with the roof rack attached;

FIG. 14 is a side view of the soft top camper shell of the present invention with the roof rack attached; and,

FIG. 15 is a top plan view of the soft top camper shell of the present invention with the roof rack attached.

The dashed lines on the soft top in FIGS. 6-15 are understood to represent stitching.

The shell in FIGS. 1-5 and the soft top in FIGS. 6-10 have been shown separately from the soft top camper shell for pickup trucks with roof racks in FIGS. 11-15 for ease of illustration.
